(57) CLAIM

The ornamental design for a sleep mask, as shown and described.

DESCRIPTION

FIG. 1 illustrates a perspective backside view of a sleep mask;

FIG. 2 illustrates a perspective front side view thereof; and, FIG. 3 illustrates a perspective overview thereof with a broken line illustration of a user wearing said sleep mask. Hook-and-loop fasteners are shown on both ends of the mask. It is understood in the art that the pattern illustrates represents a component of the hook-and-loop fasteners. The broken lines shown in the FIG. 2-3 drawing are included for the purpose of illustrating environment when the sleep mask is in use and form no part of the claimed design. The dash-dot lines appearing in FIG. 3 drawing represent an unclaimed boundary and forms no part of the claimed design.
